VANITY BOX

Le Roy Root, Stamford, Conn., assignor to Scovill Manufacturing Company, Waterbury, Conn., a corporation of Connecticut

Application October 18, 1949, Serial No. 122,110

7 Claims. (Cl. 220—32)

1

This invention relates to a cosmetic container and particularly to a vanity box for use with loose powder.

In the manufacture of the loose powder type of vanity box, it is necessary to provide an interior compartment having a cover lid to hold the loose powder within the body portion of the container. Usually the cover lid is hinged to some member within the container and some form of releasable catch for the lid is provided. Heretofore it has been necessary to employ rather complex insert members to hold the hinge elements and catch members in place and often to resort to rivets to make the attachment, which is an expensive and time consuming operation.

It is, therefore, the principal object of this invention to provide an improved loose powder type of vanity box in which the hinge member and if desired, also the catch member for the cover lid of an interior compartment may be assembled and held in place merely by the assembly of an insert member into the body compartment without resorting to rivets or other complex devices.

With the above and other objects in view the invention will be hereinafter more particularly described in conjunction with the accompanying drawing, in which:

Fig. 1 is a plan view of a vanity box container as it appears with the cover in open position.

Fig. 2 is a vertical sectional view through the box on an enlarged scale showing the cover in closed position.

Fig. 3 is a fragmentary sectional view through the hinge section of the interior compartment, the view taken along the line 3—3 of Fig. 1.

Fig. 4 is a perspective view of the hinge lug member, per se, and

Fig. 5 is a perspective and part sectional view of the body and insert ring member minus the hinge lug.

Referring now to the drawing in which like reference numerals denote like parts throughout the several views, the numeral 10 refers to a cupped shaped body having a necked-in portion 11 adjacent its upper edge. The usual form of cover member 12 is hinged to the body as at 13 and has the usual form of detent catch 14 adapted to engage with a complementary recess 14a in the body 10.

A mirror 15 may be positioned on the inside of the cover and held there in place by the usual form of bezel 16.

In order to provide for a closed compartment within the body 10 to accommodate a supply of loose powder, there is provided an insert mem-

2

ber 17 which pursuant to my invention is a plastic ring preferably of substantially square shape in cross section. The term "insert member" as used herein and in the appended claims means a holding member or powder well adapted to fit within the body member. This ring is constructed so as to have a snug telescopic fit within the interior diameter of the necked-in portion 11 and to lie against the bottom wall of the body. 5 A cover lid 18 is fashioned to fit against the upper surface of the insert member 17 and thus provide for a closed compartment or well 19 within the body member 10 for the reception of loose powder. The cover lid 18 is preferably formed 10 with an inwardly offset portion 20 dimensioned so as to snugly fit within the interior diameter of the insert ring 17 to prevent leakage at that point.

In order to provide a hinge connection between 20 the cover lid and the insert ring 17, an L-shaped hinge lug 21 is adapted to fit into a recess 22 provided in and extending about the outer and lower surfaces of the insert ring member 17. Specifically the lower leg 21a of the L-shaped 25 lug fits into that portion of the recess 22 on the under side of the insert ring 17, and the upright leg 21b fits into that portion of the recess on the outside diameter of said insert member 17. Formed integral with the upper end of the upright leg 21b is a hinge barrel 23 which preferably 30 is of a length less than the width of the L-shaped hinge lug 21. The cover lid 18 is likewise formed with a pair of spaced hinge barrels 24 which may be connected with the hinge barrel 23 as by a hinge pin 25.

It is to be noted from Fig. 3 that the hinge barrel 23 is preferably formed entirely inwardly of the upright leg 21b and is positioned so that the distance between the upper surface of the lower leg 21a and the under adjacent surface of the hinge barrel 23 may be slightly less than the width of the insert ring member 17. By this construction the hinge lug 21 can be held by frictional engagement upon the insert ring member 40 17, preliminary to the assembly of the latter member to the body 10.

If it is desired to have a releasable spring catch element for holding the cover lid in closed position, an L-shaped catch lug 26 may be provided which is of somewhat similar construction to the hinge lug 21 and may be fitted into a complementary recess 27 similar to the recess 22 at a diametrically opposite position in the insert ring member 17. The upper end of the catch lug may be formed with any suitable form

of thumb member which in this case is shown as a rolled barrel portion 28 which is adapted to engage over the adjacent edge of the cover lid 18 and may be manually sprung away in order to release said cover lid.

In the assembly of the insert ring 17, the hinge lug 21 and catch lug 26 may be placed in their respective recesses 22 and 27, after which the insert ring may be telescopically fitted into the body 10 and by reason of the snug fit that the 10 ring has with the necked-in portion 11, the hinge lug 21 and catch lug 26 will be permanently held in position.

If desired the relative positions of the hinge barrels 24 on the cover lid may be constructed so 15 that when the cover lid is in closed position it will be subjected to a tension force that will partially open the cover lid upon release of the catch lug 26.

While the invention is shown and described in 20 what we believe to be its best form, it will be understood that various changes and variations may be made in the particular structure disclosed without departing from the invention as defined in the appended claims.

What I claim is:

1. A vanity box comprising body and cover members hinged together, an insert member fitted into said body member and providing a well compartment for loose powder, said insert member being substantially square shape in cross section, a cover lid for closing the top of said insert member, an L-shaped hinge lug member engaging about the outer and under sides of said insert member and held in place against the bottom and side walls of the body member by the assembly of said insert member into said body member, said hinge lug having a hinge barrel disposed over and against the top surface of said insert member, and means hingedly connecting said cover lid to said hinge barrel.

2. A vanity box comprising body and cover members hinged together, an insert member fitted into said body member and providing a well compartment for loose powder, said insert member being substantially rectangular shape in cross section, a cover lid for closing the top of said compartment, an L-shaped hinge lug member, said insert member having a recess provided in its outside and bottom surfaces for the reception of said hinge lug, said lug being held in said recess against the bottom and side walls of the body member by the assembly of said insert member into said body member, and means for hingedly connecting said cover lid to said hinge lug.

3. A vanity box comprising body and cover members hinged together, an insert member substantially rectangular shape in cross section and fitted into said body member for providing a 60 well compartment for loose powder, a cover lid for closing the top of said insert member, an L-shaped hinge lug member, said insert member having a recess in its outside and bottom surfaces for the reception of said L-shaped hinge lug, a hinge barrel at the end of the upright leg

of said hinge lug and positioned to lie against the upper surface of insert member, and means hingedly connecting said cover lid to said hinge barrel.

5. A vanity box as defined by claim 3 wherein the position of said hinge barrel relative to the lower leg of said lug member is such as to effect a frictional engagement upon said insert member.

6. A vanity box comprising body and cover members hinged together, an insert member rectangular in cross section and fitted into said body member for providing a well compartment for loose powder, a cover lid for closing the top of said insert member, a pair of L-shaped lug members diametrically positioned on the outside of said insert member with their lower legs disposed thereunderneath, one of said lug members having means for hingedly connecting to said cover lid and the other lug member having means for releasably retaining said cover lid in closed position, and said lug members being held against the bottom and side walls of the body member by the assembly of said insert member into said body member.

7. A vanity box as defined by claim 3 wherein said insert member is provided with diametric recesses in its outer and under walls for the reception of said L-shaped lugs.

8. A vanity box comprising cup-shaped round body and cover members hinged together, said body member having inwardly necked rim adjacent its upper edge for the reception of the cover wall, a plastic ring member telescopically fitted into inner diameter of the necked ring and being substantially rectangular in cross section, a cover lid for closing against the top of said ring member, an L-shaped hinge lug member, a recess provided in the outer and under surfaces of said ring member for the reception of said lug member, said lug member being held in assembled position in said recess against the bottom and side walls of the body member by the assembly of said insert member into said body member, and means hingedly connecting said cover lid to said hinge lug member.
